Primary Examiner — Ricky Pham*(74) Attorney, Agent, or Firm* — Fredrikson & Byron, P.A.(57) **CLAIM**

We claim the ornamental design for a bungee chair, as shown and described.

DESCRIPTION

FIG. 1 is a perspective of our new design for a bungee chair; FIG. 2 is front view thereof; FIG. 3 is a rear view thereof; FIG. 4 is a right side view thereof; FIG. 5 is a left side view thereof; FIG. 6 is a top view thereof; and, FIG. 7 is a bottom view thereof.

The broken lines shown in the drawings are for illustrative purposes only and form no part of the claimed design.
